COOKING POUCH

Lester E. Bair, Brownsville, Tex., assignor to Fairshare Marketing & Manufacturing Co., Inc., Brownsville, Tex.

Filed July 3, 1972, Ser. No. 268,523

Term of patent 14 years

Int. Cl. D9—05

U.S. Cl. D9—249

FIG. 1 is a front elevational view of a cooking pouch embodying my new design; and

FIG. 2 is a side elevational view thereof.

The rear is substantially the same in appearance as the front.

I claim:

The ornamental design for a cooking pouch, as shown and described.
